UNITED STATES PATENT OFFICE.

GEORGE E. STEUDEL, OF MILWAUKEE, WISCONSIN.

HOT-BLAST STOVE.

Application filed September 15, 1921. Serial No. 500,934.

To all whom it may concern:

Be it known that I, GEORGE E. STEUDEL, a citizen of the United States, residing at Milwaukee, in the county of Milwaukee and State of Wisconsin, have invented certain new and useful Improvements in Hot-Blast Stoves, of which the following is a specification.

My invention relates to hot blast stoves and has particular reference to the checker work with which the heating chamber of these stoves is lined for the purpose of heating the air blast which is forced through these stoves before being conducted to a blast furnace. Heretofore this checker work has been constructed of a plurality of separate parallel flues formed by placing courses of fire brick in edge to edge vertical relation with each other, each course consisting of parallel extending rows of bricks spaced apart from each other in one direction, with similar rows in the same horizontal plane extending across the chamber at right angles to the first mentioned rows, each brick being placed in end to side horizontal relation with each other, each row extending in the same horizontal plane, the joints being broken in the adjacent courses for purposes of strength, and the necessary filling in done at the edges of the courses to completely fill up the space.

In the practice heretofore, it has been the custom to build up these courses one on top of the other in the same horizontal plane, which results at times in some of the upper courses shifting sidewise so that some of the flues become stopped or clogged up, with the result that the hot blast stove is decreased in efficiency and also materially lessened in capacity.

By my improved method of laying these checker work courses towards the upper part of the checker work, I place certain courses in vertical offset relation with each other so that the structure as a whole is bound together and there is much less danger of side slipping and thereby stopping up the flues.

Another and further object of my invention is the provision of a checker work lining for hot blast stoves, which is simple to put into position and which does not require removal and rebuilding such as was common in the old practice.

These and other objects of my invention

will be more fully and better understood by reference to the accompanying sheets of drawings, wherein—

Figure 1 is a vertical sectional view of a hot blast stove embodying my invention;

Figure 2 is a plan view of a section of checker work in a hot blast stove; and

Figure 3 is a sectional view on line 3—3 of Fig. 2.

Referring now specifically to the drawings, a shell 10 is shown having a dome 11 thereon and having a gas burner 12 in the lower end of said stove and an outlet 13 leading to the chimney through which the products of combustion escape. A cold air inlet 14 is provided and an outlet for the hot blast 15 is also provided, leading from the hot blast stove and from the combustion chamber 16 which extends vertically throughout the hot blast stove. A heating chamber 17 is provided having the checker work 18 located therein through which flues 19, 19 pass. The checker work in the lower portion of the shell 10 is composed of courses of fire brick 20, 20, each course consisting of rows of brick 21, 21 extending in one direction and other rows 22 extending in a direction at right angles to the rows 21, 21, each brick being laid in vertical edge to edge relation with the adjacent brick. These courses extend at right angles to each other in the heating chamber and each brick is placed in end to side relation with the adjacent brick with the joints being broken so that vertical extending flues 19 are formed throughout the combustion chamber. Beginning about twelve or fourteen courses from the top of the checker work, as at 23, rows 21^a, made up of bricks one-half the height of the usual bricks, are inserted so that the rows of bricks 22 and 23 instead of being in the same horizontal plane are in vertical offset relation with each other, and this arrangement is continued until the top of the checker work is reached, whereupon bricks of one-half the height can be used in the rows 22 to smooth up the top of the checker work, or the checker work allowed to remain with the edges broken, such as illustrated in Fig. 3.

It will thus be understood that by breaking the horizontal relation of the courses of brick in the upper part of the checker work any tendency to side-slip of the brick is

avoided and the flues 19 are kept open so that the capacity of the furnace is maintained at all times.

In the operation of the device it will be understood that gas is admitted to the burner 12 and is consumed in the combustion chamber 16, passes downward through the heating chamber 17 through the flues and outward through the opening 13 leading to the chimney, the cold air inlet 14 and the hot blast outlet 15 being closed in the meantime. Upon the gas being shut off the cold air is turned in through the inlet 14, passes into the chamber under the arches 15 and there separates because of the restricted opening in the lower portion of the flue 17 and passes upward through the flues where heat from the checker work is absorbed, then downward through the combustion chamber 16 and out through the outlet 15.

It will also be understood that the placing of the courses of brick in vertical offset relation with each other may be done in the lower part of the checker work, if desired, although I have found in practice that the weight of the checker work is usually sufficient to hold the lower courses of brick in position without danger of slipping.

It will also be understood that many hot blast stoves now in operation which must be relined occasionally because of the slipping out of position of certain of the bricks, can have the top courses of the lining taken out and replaced with my improved stove lining and that these stoves will thus be made to render service without the necessity of tearing out the whole of the lining.

While I have described more or less precisely the details of construction, I do not wish to be understood as limiting myself thereto, as I contemplate changes in form

and the proportion of parts and the substitution of equivalents as circumstances may suggest or render expedient without departing from the spirit or scope of my invention.

I claim:

1. In combination, a hot blast stove and a lining therefor comprising a checker work arranged in courses, a part of said courses being in vertical offset relation with each other and each brick being in end to side horizontal relation with each other.

2. In combination, a hot blast stove and a lining therefor comprising a checker work arranged in courses, the said courses in the lower portion of the stove being arranged on the same horizontal plane and the courses in the upper portion of the said stove being arranged in vertical offset relation with each other, the bricks comprising the said courses being arranged in end to side horizontal relation with each other.

3. In combination a hot blast stove and a fire brick checker lining therefor composed of horizontally extending courses of brick, each course composed of rows of brick spaced apart from each other and placed in end to side horizontal relation with each other and rows in the intermediate portion of said stove being arranged in the same horizontal plane with a row of bricks one-half the height of the bricks making up one of the upper courses whereby alternate courses of bricks in the upper portion of the hot blast stove are arranged in vertical offset relation with each other, the bricks throughout the entire lining being placed in end to side horizontal relation with each other and in edge to edge vertical relation with each other.

Signed at Milwaukee, Wisconsin, this 9th day of September, 1921.

GEORGE E. STEUDEL.
